UNITED STATES PATENT OFFICE.

EARL MARR, OF MINNEAPOLIS, MINNESOTA, ASSIGNOR TO MARR OIL HEAT MACHINE CORPORATION, OF MINNEAPOLIS, MINNESOTA, A CORPORATION.

OIL BURNER.

Application filed October 26, 1925. Serial No. 64,741.

My invention relates to that type of oil burner wherein the oil is delivered to a rotary atomizing cup and is thereby atomized and, under the action of centrifugal force, 5 is thrown outward through a surrounding blast of air, and the flame that takes place by combustion outward of the cup is given a substantially disc-like form. The invention is directed to highly important features, whereby the efficiency of burners of 10 the above general type is very greatly increased and certain hitherto troublesome actions are eliminated.

Generally stated, the invention consists 15 of the novel devices, combinations of devices and arrangement of parts hereinafter described and defined in the claims.

A commercial form of burner embodying the several features of my invention is 20 illustrated in the accompanying drawings, wherein like characters indicate like parts throughout the several views.

Referring to the drawings:

Fig. 1 is a vertical axial section of the 25 burner, some parts being broken away and some parts being shown in full;

Fig. 2 is a section on the line 2—2 of Fig. 1; and

Fig. 3 is an elevation showing in detail 30 the atomizing cup with fan blades applied thereto.

The burner illustrated is arranged to be placed inside of a furnace, either a steam boiler, hot water heater or hot air heater, 35 with the atomizing cup arranged to deliver above the plane where the grate is usually found. The grate, however, will usually be removed and an approximately horizontal partition placed around the upper portion 40 of the burner, so that air will be caused to pass through the interior of the burner, all as will presently be described, but, in some instances, the grate surrounding the burner will simply be covered to prevent the free 45 passage of air upward therethrough. In the burner shown, the base member of bottom support is in the form of a casting 4 arranged to be vertically adjusted by an upright screw 5 applied to a foot bearing 6. 50 This base casting 4 will be located in what is usually designated as the ashpit, quite close to the floor, and it may be extended outward through the ash door and the propelling motor, not shown, located outside of the furnace but suitably connected

to the running parts of the burner. Rigidly secured on the top of the inner end of the base casting 4 is an upright housing 7 on which, in turn, is rigidly secured an upwardly hollow pedestal 8. The housing 7 is shown as provided with an upwardly and outwardly extended flange that affords a drip pan 9 surrounding the base pedestal 8. Located above the pedestal 8, is a position concentric to the axis thereof, is a tubular casing 10 of very much greater diameter than the pedestal 8, but preferably of slightly less diameter than the drip pan 9. This casing 10, as shown, is provided with an outstanding flange 11 that is telescoped around the downturned flange of an annular bottom plate 12 having an upstanding and outwardly flaring flange 13. The plate 12 and its flange 13 are covered with highly refractory material, such as fire clay 14. 65 This just described arrangement of said parts 12, 13 and 14 is a preferred but not an absolutely essential feature, but in such preferred arrangement, the flange 11 is formed with perforations 15 that are on a radial line slightly inward of the outer portion of the drip 9, so that any unconsumed oil that may, under any abnormal conditions, be delivered onto the facing 14, will be caused to run into said drip pan. Said drip 70 pan, as shown, is provided with a discharge pipe 16 that will lead outward to a suitable point of discharge or to a suitable catch receptacle located outside of the furnace.

The housing 7 on its bottom plate is 75 formed with an axial hub 17 that is connected by an oil supply conduit 18 to an oil supply pipe 19 that leads to a suitable source of oil or fluid fuel supply, not shown, but which source of supply may be a power-driven pump, an elevated tank or a tank under pressure.

The numeral 20 indicates a vertical oil delivery pipe or tubular standard rigidly secured at its lower end to the hub 17, as shown, 80 by threaded engagement, and arranged to receive oil from the conduit 18. In the construction here illustrated and for the purpose of assembly of the parts, the tubular standard 20 is in two sections connected by a 85 threaded joint at 21. At its upper end, the upper section of the tubular standard 20 has an enlarged head 22 shown as integrally formed therewith, and this head is provided with an oil discharge conduit 23 that 90

extends radially outward and then vertically downward. The head 22 is in the form of an inverted cylindrical cup, the head of which unites with the upper end of the tubular stem 20 and the cylindrical flange of which is spaced considerably outward from the upper portion of said standard, so as to leave a space for the reduced upper end of a rotary sleeve 24. This sleeve 24 surrounds 10 the non-rotary tubular standard 20 and is free therefrom except at its lower end, where it is journaled directly on the lower portion of said standard and is provided with a worm gear 25 located immediately 15 above the flange lower end of said standard. Just below its upper end, the sleeve 24 is journaled in a suitable bearing 26 applied to the upper end of the pedestal 8.

The atomizing cup shown is a deep approximately cylindrical cup 27 provided at its upper end with an outturned flange 27^a and at its bottom having a head portion that is rigidly secured to the sleeve 24 and is located only a short distance below the cylindrical flange of the non-rotary head 22. A deep approximately cylindrical cap 28 quite closely surrounds the cylindrical flange of the head 22 and is secured to the bottom of the atomizing cup 27, preferably by 25 threaded engagement at 29. This cap 28, on the line of the bottom of the cup 27, is provided with a plurality of circumferentially spaced oil discharge ports or perforations 30. The said parts arranged within the atomizing cup, as just described, perform highly important functions which will be stated in the description of the operation.

On the exterior of its upper portion, the atomizing cup 27 is provided with circumferentially spaced blades 31 that constitute a centrifugal air blower.

The numeral 32 indicates a supplemental casing or case section, which, as shown, is telescoped into the casing 10 and is made 45 vertically adjustable by oblique cam slots 33 formed therein and engaged by studs 34 projected inward from the casing 10. The numeral 35 indicates a finger piece applied to the supplemental casing 22 for the purpose of oscillating the same to accomplish 50 its vertical adjustments. The supplemental case section 32 is formed with closely adjacent circumferentially spaced vertical slots 32^a and intervening portions 32^b, on the upper ends of which latter is supported a deflecting ring or annular plate 33. This deflecting ring quite closely but freely surrounds the flange 27^a of the atomizing cup 27 and is given a downward and outward 55 curve or inclination.

It will now be recalled that the tubular standard or upright oil supply pipe 20 and its head 22 are non-rotary, while the sleeve 24, atomizing cup 27 and cap 28 are arranged to rotate as a unit. To impart rotary

movements to said rotary parts at high speed, I have shown a driving shaft 35, which, at its inner end, is journaled in a suitable bearing 36 on the housing 7 and is provided with a worm 37, (indicated only by dotted lines in Fig. 1), which engages the worm gear 25 on the lower end of the sleeve 20. The shaft 35 will preferably be driven by a small electric motor located outside of the furnace.

Operation.

When the device is in operation, the atomizing cup 27, cap 28 and sleeve 24 will, as indicated, be rotated at high speed and the oil or fluid will be delivered upward through the tubular standard 20 and downward through the conduit 23 of the head 22 to the bottom of the rotary atomizing cup at a point inside of the rotary cap 28. The oil thus delivered will, by centrifugal force, be thrown outward through the ports 30 and will be delivered against the lower portion of the wall of the atomizing cup. Under high rotation, the oil will be spread out in a very thin film on the interior of the cup and will be worked toward the flanged upper end of the cup. When this film reaches the flanged upper end 27 of the cup, it will be in a very attenuated condition and, hence, will be discharged from the flange of the cup in the form of a very light vapor that will take approximately disc-like form. The action of the fan blades 31 under high rotation of the cup is to produce an outward blast of air, some of which will be discharged through the disc-like spray of oil vapor adjacent to the outer edge of the cup flange 27^a, but a portion of which will be commingled with the spray outward of the deflecting ring 33. The amount of air that will be delivered to the vapor spray closely adjacent to the flange of the cup and the amount that will be delivered to the vapor outward of the deflecting ring may be varied by vertical 100 adjustments of said deflecting ring.

With a burner set in any particular furnace, there is one adjustment that will produce the best results and when this adjustment is once attained, the supplemental casing 32 and the deflecting ring 33 should be fixed in such adjustment. Hence, it will be understood that the purpose of said adjustments is to once for all get the proper adjustment. In practice, I have found that the 115 adjustments may be predetermined in advance and adjustment in the completed device thereby eliminated. Fig. 1 shows the deflecting ring 33 in its uppermost adjustment, and it will be understood that it will 120 usually be set lower down than there shown. The slots or notches 32^a in the case section 32 are not absolutely necessary or desirable, because it has been found that, in the use thereof, the discharge of air radially out- 125 130

ward is more evenly distributed at all points circumferentially around the burner.

Further considering the action of the head 22 and cap 23, it may be stated that, with 5 said parts removed or eliminated, oil delivered from the tubular standard will, on first striking the walls of the atomizing cup, be more or less splashed backward onto the tubular standard and, by capillary traction 10 and by gravity, will be caused to follow said standard backward and downward through the bearings, so that the fuel oil will get commingled with and dilute the lubricating oil used in the bearings. With the arrangement described, however, any splashing that 15 takes place from the cup will be against the interior of the cap and as the cap rotates with the cup, the fuel oil will be thrown outward and backward onto the cup and will 20 not work itself backward to the tubular standard or non-rotary supply pipe. Moreover, if, in time, carbon should accumulate on the interior of the cup and on the exterior 25 of the cap, such carbon may be readily removed by the insertion of a suitable tool or scraper, while the cup and cap are being rotated, and such tool or scraper will then scrape and completely clean not only the inner surface of the cup but the outer 30 surface of the cap.

From what has been said, it will be understood that the commercial device shown is capable of very considerable modification within the scope of the invention herein 35 described and claimed.

What I claim is:

1. In a centrifugal oil burner, the combination with an upright non-rotary oil delivery pipe provided with a distributing 40 head having a downturned oil delivery conduit offset from the axis thereof so as to deliver the oil radially outward of said oil de-

livery pipe, a rotary sleeve journaled around said oil delivery pipe, an open deep atomizing cup secured to said sleeve for rotation therewith, and an inverted cup-shaped cap enclosing said distributing head and secured at its lower portion to the bottom of said cup for rotation therewith around said cup, said cap being open at its lower portion for the 45 discharge of oil to the bottom of said cup, the upper end of said sleeve being extended upward within said cup and terminated close to the top of said cap.

2. In a centrifugal oil burner, the combination with an upright oil delivery pipe provided with a downturned head having a downturned oil delivery conduit offset from the axis thereof, a rotary sleeve journaled around said oil delivery pipe with its upper 50 end extended between the upper portion of said pipe and its depending delivery conduit, a deep open atomizing cup secured to said sleeve for rotation therewith, and an inverted cup-shaped cap enclosing the upper 55 end of said sleeve and the downturned head of said oil delivery pipe, said cap being secured to the bottom of said cup but spaced from the walls thereof and having circumferentially spaced oil delivery ports for the 60 discharge of the oil to the lower portion of said atomizing cup.

3. The structure defined in claim 2 in which said atomizing cup and said cap have approximately cylindrical walls. 75

4. The structure defined in claim 2 in which said atomizing cup and said cap have approximately cylindrical walls, and in which the head of said oil delivery pipe is approximately cylindrical and lies close to 80 the exterior of the upper end of said sleeve and to the interior of said cap.

In testimony whereof I affix my signature.
EARL MARR.
